EAR CLIP

Irving Berzner, Rockville Centre, N.Y., assignor to Nomo Products, Inc., Johnston, R. I., a corporation of Rhode Island

Filed June 22, 1964, Ser. No. 80,501

Term of patent 14 years

(Cl. D45—9)

FIG. 1

FIG. 2

FIG. 4

FIG. 1 is a perspective view of an ear clip showing my new design;

FIG. 2 is a front elevational view thereof, on an enlarged scale;

FIG. 3 is a side elevational view, looking from the left with respect to FIG. 2; and

FIG. 4 is a side elevational view, looking from the right with respect to FIG. 2.

The dominant features of my design reside in the full-line portions on the drawing.

The side opposite that shown in FIG. 2 is substantially similar in appearance. The broken line showing of the pendant has been omitted from FIGS. 2, 3, and 4 for convenience of illustration.

I claim:

The ornamental design for an ear clip, substantially as shown and described.
